CLAIM

The ornamental design for the bottle for cosmetics, as shown and described.

DESCRIPTION

FIG. 1 is a perspective view of a bottle for cosmetics showing my new design;

FIG. 2 is a front view thereof, the rear view being symmetrical to the front view;

FIG. 3 is a top plan view thereof;

FIG. 4 is a bottom view thereof;

FIG. 5 is a left side view thereof;

FIG. 6 is a right side view thereof; and,

FIG. 7 is a perspective view shown with the cap removed for a clear disclosure of the underlying parts.

The broken lines depict the portions of the bottle for cosmetics that form no part of the claimed design.
